UNITED STATES PATENT OFFICE.

WILLIAM H. HUGGINS AND JOHN F. WADDELL, OF MORRISTOWN, TENNESSEE.

ADJUSTABLE WINDOW-SHADE HANGER.

1,114,882.

Specification of Letters Patent. Patented Oct. 27, 1914.

Application filed October 18, 1913. Serial No. 795,881.

To all whom it may concern:

Be it known that we, WILLIAM H. HUGGINS and JOHN F. WADDELL, citizens of the United States, residing at Morristown, in the county of Hamblen and State of Tennessee, have invented new and useful Improvements in Adjustable Window-Shade Hangers, of which the following is a specification.

10 The invention has for one of its principal objects the provision of a simple construction in such devices whereby a minimum number of parts and assembly operations will be required while yet attaining high 15 efficiency in ease of operation and simplicity of installation and manipulation.

We are aware that devices with similar functions and superficially resembling ours have been produced, and it is the aim to 20 effect improvements on these in certain particulars, which, while not working a markedly noticeable change of form, have an important effect on the availability of the device for the general public.

25 We use the familiar grooved guide strips attachable to the sides of an ordinary window frame at its upper part, in which slides a roller carrier upon which the shade roller is carried, and it is a particular object to give a construction of the guide 30 pieces proper which will permit the manipulation of the device with one hoisting cord, enable the rigid attachment of a cross piece therebetween, and afford a satisfactory support 35 for the roller trunnions in a proper location with respect to the sides of the window frame, using a small amount of metal.

Other objects and advantages may appear, or may be apparent from the following 40 description and drawings, in which—

Figure 1 is a front view of a window equipped with our invention, Fig. 2 is a side view thereof, Fig. 3 is a detail of one of the 45 guide pieces, Fig. 4, is a top view of the hanger.

There is illustrated a window frame 10 of ordinary form and construction, on each side of which at the upper part there are mounted respective guide strips 11 having 50 grooved edges presented toward the inner side of the window frame or opening. The grooves stop short of the lower ends of the strips but extend through the upper ends. A small pulley 12 is mounted centrally of 55 the top of the frame and a second one 13 is disposed at the side outwardly of the adj-

cent strip 11, a cord 14 being extended through these pulleys and down to a cross bar 15 of the shade carrier, the outer end of the cord being of sufficient length to be engaged with the cleat 24 mounted at a suitable height on the outer side of the frame 10. At each end of the bar 15 there is mortised a guide piece 16, stamped integrally from sheet metal, the mortising being very 60 simple and involving only a kerf in each end of the bar which bar may be made of any wood or other material. The guide piece includes a horizontal arm 17 on its inner side, having longitudinally spaced 65 apertures (see Fig. 3), through which mortise pins 18 or other suitable fastenings are engaged and fixed in the bar 15. The ends of the latter are spaced from the guide strips, and the guide pieces project outwardly thereof their major body portion being located outwardly and downwardly of the bar. This body is considerably longer than the arm 17 and extends from the upper edge thereof downwardly for four inches or 70 more in the appliance as constructed for small domestic windows. Its outer vertical edge is rectilinear and uninterrupted throughout the length of the body, which is important in preventing binding of the 75 guide pieces in use. An extension 19 is formed on the inner edge of each guide piece having an upper side spaced slightly beneath the arm 17 in which there is formed the angular notch 20 on one guide piece, 80 and an aperture 21 is formed in the extension 19 of the other guide piece on a level with the bottom of the notch 20. The extension may be of ornamental form, and the arrangement of the elements of this guide 85 piece is such that by taking the blanks from the stock in the manner shown in Fig. 4, there is practically no waste, notwithstanding the peculiar contour of the blank required to provide an arm 17 of sufficient 90 length to afford a rigid jointure with the bar 15, the shorter length of the extension 19, and the desirability of having the body of the piece extend below the part 19 in order to give the necessary length thereto 95 to prevent binding. With the construction shown the device has been found to operate very smoothly in practice, with the single point of support.

The cleat comprises a single length of 100 wire bent into an elongated U-shape centrally, and the outer parts of the arms

curved oppositely outward in the plane of the central part. The inner parts of the arms may be nicked or shouldered as at 22 on their outer sides if desired whereby the 5 cleat will be more securely anchored when put in place, as will be described. A small hole is bored to receive the central part of the cleat and after insertion a small plug 23 slightly less in length than the U-shaped 10 part is driven between the arms, being of a sufficient size to force the arms apart and into the wood or other material in which the cleat is fastened.

What is claimed is:

- 15 1. A curtain shade hanger comprising two guide members constructed and adapted to be attached to a window frame, a transverse bar, sheet metal guide pieces having inwardly extending arms engaged with the 20 bar, and having outer rectilinear edges extending a considerable distance in a vertical direction from the arms and engaged slidably with the guide members, extensions formed on the inner parts of the guide 25 pieces shaped and arranged for engagement with shade roller trunnions, and flexible

hoisting means engaged with the bar and operable from one side of a window.

2. As an improved article of manufacture, a guide piece and corner piece for a 30 carrier of the class described formed integrally from sheet metal and comprising a vertical body portion, a horizontal broad arm projected from the inner edge thereof, and an extension spaced beneath the arm having a portion formed to support a shade 35 roller trunnion intermediately of the height of the body when turned laterally, the extension being spaced from the bottom a distance corresponding to the width of the 40 outer end of the extension, and being shorter than the arm by the width of the vertical portion, whereby the pieces may be produced with a minimum waste.

In testimony whereof we have hereunto 45 set our hands in presence of two subscribing witnesses.

WILLIAM H. HUGGINS.
JOHN F. WADDELL.
